[57] **ABSTRACT**

A Gatling-type machine gun with a rotating barrel cluster is provided with a barrel clamp to secure the barrels against displacement effected by centrifugal forces and a unitary flash suppressor assembly comprising a plate with integral flash suppressors equal to the number of the barrels extending from the plate in registry therewith. The flash suppressor assembly is interlocked with the barrel clamp and the barrel cluster to prevent relative rotational displacement and to permit longitudinal displacement thereof relative to the flash suppressor assembly responsive to thermal expansion.

FLASH SUPPRESSOR ASSEMBLY FOR GATLING-TYPE MACHINE GUNS

BACKGROUND OF THE INVENTION

This invention relates to flash suppressor attachments to barrels and pertains more particularly to a unitary flash suppressor attachment to the barrel cluster of Gatling-type machine guns.

With Gatling-type machine guns which comprise a rotating cluster of barrels the barrels must be held in correct relationship to each other against the centrifugal forces created by the rotation. This problem is overcome by adding to the barrel cluster clamping means which hold the barrels in correct relationship. This, of course, creates quite a complex barrel cluster assembly which presents problems when it comes to mounting a flash suppressor assembly, in addition, to the barrel cluster. The problem which has caused considerable concern is the lack of a positive means for locking the flash suppressor assembly to the barrel cluster. The best of several devices used up until the present is a threaded bolt screwed into a nut which has deformed threads to provide a frictional restraint between the two parts, but which nevertheless frequently becomes loose upon firing of the weapon. In addition, the present flash suppressor assembly consists of separate flash suppressors which are threaded into a supporting plate, which is costly because considerable machining is required.

SUMMARY OF THE INVENTION

The locking problem is overcome by the present invention which provides structure for positively locking the flash suppressor to the barrel clamp through a bolt-nut assembly wherein the head of the bolt is prevented from turning by the blocking contact of the head with flash suppressors in the flash suppressor assembly and the nut is blocked against turning by having the clamp retaining bolt, which passes through the clamp and the barrel cluster, also pass through a cross-hole in the nut. The use of an investment casting for fabricating the flash suppressor assembly as a unit reduces considerably the amount of machining required and therefor its manufacturing cost.

Further advantages of the invention will be apparent from the following specification and the accompanying drawings which are solely for the purpose of illustration.

BRIEF DESCRIPTION OF THE DRAWINGS

FIG. 1 is a front end view of the flash suppressor assembly mounted to a barrel cluster;

FIG. 2 is a cross-sectional view taken along line 2—2 of FIG. 1; and

FIG. 3 is a cross-sectional view taken along line 3—3 of FIG. 2.

DESCRIPTION OF A PREFERRED EMBODIMENT

Shown in the drawings is a flash suppressor assembly 12 which is replaceably mounted to a Gatling-type machine gun, such as the M134 Aircraft Machine Gun, 7.62 mm, having a rotatable barrel cluster 14. Such barrel cluster 14 comprises six barrels 16 which are mounted to a rotatable firearm structure (not shown) so as to be symmetrically disposed equidistant apart

and equidistant from the central longitudinal axis of the barrel cluster, and which are securely held together by a barrel clamp 18 against the centrifugal forces generated when the barrel cluster is rotated.

Barrel clamp 18 includes a cylindrical tube 20 with a bore 22 which is counterbored from muzzle end 24 at 10 26 and from breech end 28 and 30. Three front discs 32 integral with tube 20 are spaced apart along the forward portion thereof so as to be normal to the longitudinal axis thereof, and located at breech end 28 is an integral rear disc 34 with a cylindrical skirt 36 which extends rearwardly from the periphery thereof parallel to the longitudinal axis of tube 20. Front discs 32 and rear disc 34 are provided with holes 38 which are longitudinally aligned to receive barrels 16. Provided along the muzzle end half of the barrels 16, are four annular front flanges 40 which are slidingly received by the respective holes 38 in front discs 32 and rear disc 34 20 and an annular rear flange 42, with a front side 43 and a rear side 45, is located on each of the barrels so that the front side has contact with the rear side of disc 34 when the front flanges are located in their respective holes. Located diametrically apart in skirt 36 are two holes 44 25 which receive a retaining bolt 46, as shown in FIG. 3, so that the bolt is located between opposite pairs of barrels 16 and has contact with rear sides 45 of rear flange 42 thereon. Thus, barrel clamp 18 is secured against longitudinal displacement relative to barrel cluster 14 30 with front sides 43 of rear flanges 42 on the engaged barrels 16 having contact with disc 34 and rear sides 45 contacting bolt 46 which is anchored to barrel clamp 18. Bolt 46 is secured by a nut 47.

Flash suppressor assembly 12 comprises a flash suppressor cluster 48 and a bolt 50 with a cooperating nut 52 for securing the flash suppressor cluster to barrel clamp 18 as hereinafter described. Flash suppressor cluster 48 is preferably fabricated as an investment casting to comprise as a single unit a circular plate 53 with six flash suppressors 54 extending forwardly integrally therefrom. Plate 53 is provided with an orifice 56 in coaxial relationship with each of the flash suppressors 54 to provide communication between the related barrel 16 and the flash suppressor and to receive the muzzle end of the barrel. When flash suppressor assembly 12 is mounted on barrel cluster 14 a central boss 58 extending rearwardly from plate 53 is matingly seated in counterbore 26. An axial aperture 60 through 35 plate 53 and boss 58 receives bolt 50. Each of the flash suppressors 54 include five bars 62 which extend forwardly from front face 63 of plate 53 around the respective orifice 56 and such bars are separated by spaces 64. Bars 62 and spaces 64 are so arranged that a space is located diametrically opposite the inner face of each of the bars according to good flash suppressor design.

Bolt 50 comprises a shaft 66 with a hexagonal head 68 centrally formed at one end thereof. The opposite end of shaft 66 is provided with a threaded section 70 which is engaged by nut 52. Head 68 is dimensioned so as to be insertable within flash suppressors 54 with each of the six points 72 thereof located between a pair of the flash suppressors, as shown in FIG. 1, whereby bolt 50 is prevented from rotational displacement relative to flash suppressor cluster 48. When head 68 is in contact with plate 53, shaft 66 extends from tube 20 so that

threaded section 70 is engageable by nut 52. Nut 52 includes a cylindrical portion 74 which is receivable by counterbore 30 so as to center the nut relative to barrel clamp 18 and a shoulder 76 which contacts breech end 28 thereof. A cylindrical boss 80 extends rearwardly from nut 52 and such boss is provided with a diametrical cross-hole 82 for receiving bolt 46.

Thus, when flash suppressor assembly 12 is combined with barrel clamp 18 and they are assembled to barrel cluster 14, the barrel clamp is secured against rotation relative to the barrel cluster through the engagement of barrels 16 with holes 38 in discs 32 and 34 and the flash suppressor is secured against rotation relative to the barrel cluster through the engagement of the muzzle ends of the barrels with orifices 56. In fact, through the engagement of the muzzle ends of barrels 16 with orifices 56 flash suppressor assembly 12 assists barrel clamp 18 in holding the barrels in the proper relationship. Barrel clamp 18, further, is prevented from longitudinal displacement relative to barrel cluster 14 through the engagement of rear disc 34 with front sides 43 of rear flanges 42 and of bolt 46 with rear sides 45 of the rear flanges on the engaged opposite pairs of barrels 16. Through barrel clamp 18, flash suppressor assembly 12 is secured against longitudinal displacement relative to barrel cluster 14 because, when nut 52 is tightened on bolt 50, plate 53 is held in contact with the front end of the barrel clamp and the nut has contact with the barrel clamp at the rear end thereof. Nut 52 is prevented from unloosening through the engagement of bolt 46 with cross-hole 82. Thermal expansion of barrels 16 relative to the assembly of barrel clamp 18 and flash suppressor assembly 12 forwardly of rear flange 42, is permitted by the sliding engagement of front flanges 40 with holes 38 in discs 32 and by sufficient clearance being provided in orifices 56 for longitudinal displacement of the muzzle ends of barrels 16 by the thermal expansion.

I wish it to be understood that I do not desire to be limited to the exact details of construction shown and described, for obvious modifications will occur to a person skilled in the art.

I claim:

1. In a machine gun comprising a rotating barrel cluster including a plurality of symmetrically arranged barrels, the improvement comprising in combination with said barrel cluster, a barrel clamp for securing said barrels together against centrifugal forces in properly spaced relationship, said barrel clamp comprising a central tube, at least one front disc located at the muzzle end of said tube normal to the longitudinal axis thereof, a rear disc located at the breech end of said tube normal to the longitudinal axis thereof, longitudinally aligned holes through said front and rear discs for receiving said barrels, front flanges equal to the number of said front discs integrally formed on the forward portion of each of said barrels for registry with

said front discs and for sliding contact therewith at said holes, a rear flange including a front side and a rear side integrally formed on each of said barrels, said rear flange being located so that said front side has engagement with said rear disc, a skirt extending rearwardly from the periphery of said rear flange, and a retaining bolt extending diametrically through said skirt and between said barrels in said barrel cluster for contact with said rear sides of said rear flanges on opposite pairs of said barrels to secure said barrel clamp, in cooperation with said disc, against longitudinal displacement relative to said barrel cluster, and a flash suppressor assembly respective to said barrels held in interlocked relationship with said barrel cluster and said barrel clamp.

2. The invention as defined in claim 1 wherein said flash suppressor assembly comprises a flash suppressor cluster including a circular plate and a plurality of flash suppressors equal to the number of said barrels extending integrally from said plate in respective registry with said barrels.

3. The invention as defined in claim 2 wherein each of said flash suppressors comprises a plurality of bars in spaced relationship, and said plate is provided with orifices coincident with said flash suppressors for slidably receiving the muzzle ends of said barrels and providing communication between said barrels and said flash suppressors.

4. The invention as defined in claim 3 wherein said flash suppressor assembly comprises a bolt and a cooperating nut functionally disposed between said flash suppressor cluster and said barrel clamp for securing said flash suppressor assembly to said barrel cluster.

5. The invention as defined in claim 4 wherein said bolt includes a geometrically shaped head insertable within said flash suppressors, said head being provided with points equal to the number of said flash suppressors with each of said points being receivable between adjacent ones of said flash suppressors to prevent rotation of said bolt relative to said flash suppressor cluster, and including a central bore through said plate for passage of said bolt therethrough and through said tube to extend rearwardly therefrom, and means for mounting said nut on the extending end of said bolt for displacement against the rear end of said clamp when tightened thereagainst, and means for centering said nut relative to said tube.

6. The invention as defined in claim 5 and including a cross-hole through said nut for receiving and retaining bolt of said barrel clamp to secure said nut against displacement relative thereto.

7. The invention as defined in claim 5 wherein said orifices are dimensioned to permit relative longitudinal displacement of said muzzle ends therein responsive to thermal expansion of said barrels forwardly of said rear flanges.
